UNITED STATES PATENT OFFICE.

JOHN DALL, OF NEW YORK, N. Y.

COAL-BUNK.

SPECIFICATION forming part of Letters Patent No. 295,233, dated March 18, 1884.

Application filed January 25, 1884. (No model.)

To all whom it may concern:

Be it known that I, JOHN DALL, a citizen of the United States, residing at New York, in the State of New York, have invented a new and useful Improvement in Coal-Bunks, 5 of which the following is a specification.

The nature of my invention consists in the construction of a bunk or receptacle for coals, to facilitate the unloading of coal barges or 10 ships, and prevent the delay occasioned in the waiting for the coal-carts to carry the coal away.

In the accompanying drawings, Figure I represents a front view, and Fig. II a side 15 view, of my improved coal-bunk. Fig. III is a top view of part of the bunk.

Similar letters represent similar parts in all the figures.

A is a receptacle, the sides and back of 20 which are made slanting toward the front, in which a large opening is made, closed by a suitable door, B, hinged at its upper edge to the front of the receptacle, opening outward. The door is fastened to the spindle a, on the 25 end of which a crank, c, is attached, connected through a rod, b, to a lever, D, through which the door B is operated, so as to close or open when desired. To the lever D a spring, S, is attached, acting in such a manner on 30 said lever as to close the door B. The upper part of the lever D works in a guide-frame, J, attached to the side of the bunk A, provided at its inside with recesses n n'—one at each end—into which the lever D is moved or

sprung at each end of its movement, to hold 35 said lever, and consequently the door B, in its relative position—viz., either open or closed.

While unloading a coal-barge the coal is hoisted out of the barge with buckets, and generally emptied directly into the cart, to be 40 carted away. In this operation considerable delay is occasioned during the moving away of one cart and the backing up of the next cart. By the employment of my improved coal bunk or bunks the unloading can proceed 45 even when no cart should be ready to receive the coal, and the cart moved to one of the bunks, to be filled almost instantaneously, and whereby much time, and consequently expense, will be saved. 50

These bunks are very light, and can readily be moved into any desired place. These bunks, if desired, may be divided in the center by a partition, and supplied, in that case, with a door for each partition. 55

What I claim as my invention, and desire to secure by Letters Patent, is—

A receptacle, A, the sides and back of which are made slanting toward the front, closed by a hinged door, B, in combination with crank 60 c, rod b, lever D, spring S, and guide-frame J, provided with recesses n n', arranged to operate in the manner and for the purpose substantially as described.

JOHN DALL.
